UNITED STATES PATENT OFFICE

CLARENCE C. SHIPP, OF INDIANAPOLIS, INDIANA

RADIATOR-BOX BASE

Application filed May 8, 1929. Serial No. 361,507.

This invention is an improvement on box bases for steam radiators such as are shown in my Patent No. 1,711,814 issued May 7, 1929, and the object here is to extend the parts 5 of the two-part box ends above the circular pipe opening so as to obviate the requirement of a separate plate to complete the closure.

A further object is to unite the meeting edges of the ends above the base openings by 10 slip joints which will keep the edges from buckling open in use while allowing the back of the box to be assembled first on the radiator and the front then placed in position.

Another object is to unite the vertical end 15 edges of the radiator box by slip-joints to keep them always closed practically air-tight, and also to unite their lower edges to the box base by slip joints into channel bars at the ends as well as at the front and back sides of 20 the box.

I accomplish the above, and other objects which will hereinafter appear, by the means illustrated in the accompanying drawing, in which—

25 Fig. 1 is a view in front elevation of a steam radiator equipped with my invention; and

Fig. 2 is a perspective view of the box base without the radiator, broken away in part, and with fragments of the walls of the box 30 assembled in operative position with the base.

Like characters of reference indicate like parts in the several views of the drawing.

The radiator coils 1 are of usual construction with communicating openings surrounded by bosses 2 from which bosses the box base 3 is suspended by inverted U-shape hangers 4, 4, the stems of which pass through eyes 5 projecting from the base.

40 6 is the radiator containing box, and as the box and base are assembled on the radiator after the latter is installed, the box and base are in longitudinally separable parts.

The back wall of the box base has a tubular extension 7 of the size and shape of the air duct in the wall of the house to the outside air, and the rear section of the box base has a bottom opening which is provided with a door 8 hinged at its rear edge and swinging 50 downwardly and rearwardly to open.

The ends 9, 9, of the base have openings 10 for the passage therethrough of the bosses 2 of the radiators, one-half of the openings being formed in the front and back parts respectively of said ends. The separation of the 55 base into two parts, front and rear, is by dividing the ends 9 on lines 12, which begin at the front corners of the bottom door opening and extend upwardly diagonally to the middle of the openings 10, and lines 13 which 60 extend vertically from the middle of openings 10. A channel member 17 is spot welded to the rear portion along line 13 and this channel receives a tongue 18 extended from the front member to the end, thus forming a 65 slip joint.

An angle bar 19, is riveted to the inside of the bottom and end of the back base member, with an extension against the end of the front base member, preferably removably secured to the latter by screws for greater convenience in installation. 70

The walls of the radiator box 6 are formed 75 out of sheet metal, preferably corrugated vertically, in two members with the line of separation for the joint vertical midway of the ends. They are united by a slip joint 14.

Channel bars 15 and 16, S-shaped in cross section and formed out of a strip of sheet metal, preferably corrugated, have one edge 80 hooked respectively over the front and back walls of the base box and similarly bars 20 and 21 are hooked over both of the end walls. Into all of which bars the corresponding lower ends of the radiator box 6 are assembled 85 and held in slip joints. The channels of the slip joints 14 at the ends of the box 6 are removed at their lower ends sufficiently to avoid interference with the channel bars 16. By placing the bars 20 and 21 across the ends of 90 the box 6, the two pieces of each end are held in a straight line thereby and prevented from springing laterally one from the other. It is also to be noted that the top edges of the back, front, and two end walls of the box 3 are all 95 at the same level.

Having thus fully described my invention, what I claim is:

1. A radiator box base having front and rear walls connected by two ends, said ends 100

- having openings for the passage of radiator bosses, and said box base being in two longitudinally divided parts the joint for which passes vertically through the centers of the boss openings forming separated edges, and means comprising a channel bar having an inverted U-shaped under side frictionally engaging over both the inner and outer sides of the top edges of the two parts of the respective ends for maintaining the two parts in the same respective planes.
- 5 2. A radiator box base having front and rear walls connected by two ends, said ends having openings for the passage of radiator bosses, and said box base being in two longitudinally divided parts the joint for which passes vertically through the centers of the boss openings forming separated edges, and means comprising slip-joints for uniting said edges, channel bars for the front, rear, and each end wall, having a turned edge hooked over a respective edge thereof and forming a lock for the divided ends, and a two part longitudinally and vertically divided radiator box seated in all four of said channel bars, the vertical connecting edges of said box being united by slip-joints.
- 10 3. A radiator box base having front and rear walls connected by two ends, said ends having openings for the passage of radiator bosses, and said box base being in two longitudinally divided parts the joints for which pass vertically through the centers of the boss openings forming separated edges, and means comprising slip-joints for uniting said edges, each of said base box parts having end eyes and a U-shaped hanger suspended from a radiator boss and having legs secured in said eyes.
- 15 40 In testimony whereof I affix my signature.
CLARENCE C. SHIPP.
